Barnett Kaplan Inventor

UNITED STATES PATENT OFFICE.

BARNETT I. KAPLAN, OF NEW YORK, N. Y.

CORSET-COVER.

1,299,957.

Specification of Letters Patent. Patented Apr. 8, 1919.

Application filed April 26, 1917. Serial No. 184,662.

To all whom it may concern:

Be it known that I, BARNETT I. KAPLAN, a citizen of the United States, residing at No. 975 Second avenue, in the city of New York and State of New York, have invented 5 a new and useful Improvement in Corset-Covers, to be known as a "Camisiere," of which the following is a specification.

My invention relates more particularly 10 to improvements in corset covers made of any material worn under sleeveless evening dresses or sheer lace sleeves and very low cut backs to waist line.

Referring to drawings, the garment is 15 composed of one or more pieces of silk or batiste for front piece, terminated at the sides underneath the arms with whalebone or steel, and a belt around waist, and two side bands attached from top of whalebone to 20 belt.

Referring to the drawings:

Figure 1 represents a front view of the camisiere on a user, Fig. 2 is a side of Fig. 1; Fig. 3 is a rear view of Fig. 1 and Fig. 4 25 represents a perspective side view of camisiere with a detachable back piece.

The front section of the camisiere is shown at A. B is a belt attached to the lower portion of the front section extending 30 around the waistline of the wearer. C, C¹, C² indicate pin-tucks in the front piece to secure a good fit on the user.

In Fig. 2, is plainly indicated how the camisiere is kept in an upright position; E 35 is a pocket which extends from top of camisiere, G, to belt at point H. The pocket E contains a whale bone which holds camisiere up in right position; F is a band connected from top of the pocket at point G to the belt

at point I, which band supports or holds 40 camisiere in place.

Fig. 3 shows the belt B fastened with buckle D, which belt may be regulated by the buckle according to measurement of waist line.

In Fig. 4 is shown a detachable back piece J which can be attached to the front section A by means of the buttons or clasps K, K, K, and fastened thereto on both sides at points L, L, L. If wearer desires to wear any other 50 garment with back covered, she may add extra attachment, which covers back entirely underneath garment.

Having described my invention what I desire to secure by Letters Patent and claim is: 55

1. In a corset cover and brassière the combination of a front section, a belt connected to the lower end of the section, a pocket at each end of the section extending from the upper portion of the section to the belt, a 60 sustaining member in each pocket and a band connecting the upper end of each pocket and the belt.

2. In a corset cover and brassière the combination of a front section, a belt for the 65 lower end of the section, a sustaining member at each side end of the front section, a band connecting the upper side end of the front section and said belt and a detachable back piece for the front section. 70

In testimony whereof, BARNETT I. KAPLAN, has signed his name to this specification in the presence of two subscribing witnesses, this 24th day of April 1917.

BARNETT I. KAPLAN.

Witnesses:

HARRY APPELBAUM,
HYMEN LIEBERMAN.
